ILLUMINATED INSTRUMENT DIAL AND
THE LIKE

Lester R. Gasper, Chicago, Ill.

Application July 1, 1940, Serial No. 343,421

3 Claims. (Cl. 40—130)

The invention here disclosed relates to the decorating of glass and other transparent materials, particularly for such uses as clock dials, radio dials, instrument dials, signs and the like, and as to certain features is a continuation in part of Patent 2,207,585 of July 9, 1940.

Special objects of the invention are to create the effect of depth or third dimension in letters, numerals, ornaments, trade-marks, borders or other designs applied to the glass or other transparent material and to cause such characters to stand out with a certain solidity or cameo-like appearance.

Further objects of the invention are to create certain pleasing and attractive effects, in color as well as in form and to provide instrument dials and the like in which the numbers or other characters will be easily readable under either daylight or artificial illumination.

Additional objects and the novel features of invention by which all such objects are attained will appear or are set forth in the following specification.

In the drawing accompanying and forming part of the specification, several different embodiments of the invention are illustrated but, as will appear, the actual structure may be modified and changed in various ways all within the true intent and scope of the invention as hereinafter defined and claimed.

Fig. 1 is a face view of a panel of glass or like material decorated to constitute one embodiment of the invention.

Fig. 2 is a sectional view as on line 2—2 of Fig. 1.

Fig. 3 is a face view of another form of the invention.

Fig. 4 is a sectional view as on line 4—4 of Fig. 3, illustrating edge lighting of the same.

Fig. 5 is a face view and Fig. 6 a section as on line 6—6 of Fig. 5, illustrating another form of the invention.

In the several views, 7 designates a sheet or layer of so-called transparent material such as glass, or one of the plastics, for instance, Celluloid, Pyralin, Cellophane, Vinylite, Lucite and the like.

The decorative characters, which may be letters, numerals or other representations are made up of a design 8, on the face of the transparent sheet and a correspondingly shaped design 9, on or at the back of the same sheet and in register with the design on the face.

In the present disclosure, the design on the back is larger than that on the front, so that

5 in the various normal positions from which the designs may be viewed, a considerable portion of the design at the rear will be visible through the intervening glass or other medium, appearing through the glass as part of and joined with the figure at the front.

Generally, the back figure is enough larger than the front figure to be visible through the glass, about the edges of the front figure. This 10 provides a sense of perspective when looked at from directly in front at a normal viewing distance and when viewed from different angular positions, makes the figure appear as though extending solidly from front to back through the intervening transparent material.

In the first form of the invention shown, Figs. 1 and 2, the smaller design on the front of the transporting medium is lighter in color or appearance and the corresponding larger design on the back is darker or more opaque in character. This produces the effect indicated in Fig. 1 of a light faced character with darkly outlined spreading side edges extending through to the back of the panel.

Figs. 1 and 2 illustrate further that if desired, a background 10, may be provided about the figures on the back of the panel. This background may be in contrast with the back figures, that is, either darker or lighter. In the illustration, the back figures 9 are represented as fully opaque or solid black and the background 10, as lighter in shade and less opaque or translucent, but this relation may be reversed and otherwise varied.

35 The particular relations may depend to some extent on the manner in which the article is to be illuminated, that is, whether it is planned for simply daylight illumination or whether it is to front or back lighted, or projected lighting, or edge lighting is to be employed. Also conditions and relations may be controlled to some extent by the character of the panel.

Figs. 3 and 4 illustrate a case in point. In this embodiment, the panel is ordinary commercial glass of the kind having a greenish cast and illumination is effected by edge lighting at 11. In this instance, the smaller, front figures 12 are brown or some other dark color, so as to be easily read in daylight and the back figures 13 of corresponding but larger outline are of lighter color, preferably a translucent white.

Edge illumination of this combination produces a particularly striking and pleasing effect. The green cast of the glass is taken up by the translucent white back outline, providing the effect of

a rearwardly enlarging luminous greenish mass between the design on the front and the design on the back, or the effect of a dark front figure with a pale green rearwardly extending divergent border.

The edge lighted commercial greenish glass provides inherently a method of coloring which is useful where a greenish tint is desirable or not objectionable. Where other coloring is required, a water white glass may be used such as indicated in Figs. 5 and 6. Desired coloring may be projected through the glass in such instance by applying an edge coating of color at 14 and, shining the edge light 11, through that. Such lighting may be varied by using a colored lamp or lamps such as represented at 11a in Fig. 5. In this view, with an orange colored edge coating 14, and a red lamp 11a, with dark front figures 12 and translucent white back figures 13, the figures appear dark, surrounded by pale orange 20 red rims extending rearwardly with an enlarging effect and with the figures as a whole apparently suspended in a reddish appearing medium. The glass or other transparent medium may be flat or curved or prismatic, according to purpose or effects desired. While referred to as transparent, it will be appreciated that the degree of relative transparency may vary, depending on the particular kind of material or the quality or character of material employed for the panel. The 25 figures or designs may be applied in different ways, depending on use and purpose of the articles.

What is claimed is:

1. As a new article of manufacture, a layer of transparent material, designs of corresponding outline in registration at the front and back of said transparent layer, said designs being of contrasting shades and the design at the front being lighter in shade and substantially translucent, the design at the back being darker in shade and substantially opaque and said design at the 10 back being larger in outline than the design at the front.
2. As a new article of manufacture, a single layer of transparent material, designs of corresponding outline in registration at the front and back of said layer of transparent material, said designs being of contrasting shades and the designs at the back being of larger outline than those at the front and means for edge lighting said layer of transparent material.
3. As a new article of manufacture, a single layer of transparent material, designs of corresponding outline in registration at the front and back of said layer of transparent material, said designs being of contrasting shades and the designs at the back being of larger outline than those at the front, means for edge lighting said layer of transparent material, said material having an inherent color tint and said designs on the back being of a character to absorb said color tint from said edge lighting.

LESTER R. GASPER.
